CLAIM

I claim the ornamental design for a bowl, as shown and described.

DESCRIPTION

FIG. 1 is a perspective view of a bowl according to the new design;

FIG. 2 is a right side view of the bowl shown in FIG. 1, the left side being a mirror image thereof;

FIG. 3 is a top view of the bowl shown in FIG. 1;

FIG. 4 is a front view of the bowl shown in FIG. 1;

FIG. 5 is a rear view of the bowl shown in FIG. 1; and,

FIG. 6 is a bottom view of the bowl shown in FIG. 1.

Features shown in broken lines in the drawings are not part of the claim.

1 Claim, 4 Drawing Sheets
